UNITED STATES PATENT OFFICE.

FREDERICK W. DUSCHE, OF EAST ORANGE, NEW JERSEY, ASSIGNOR OF ONE-HALF TO
LEON M. NUSSBAUM, OF NEWARK, NEW JERSEY.

SHOE-SHINING DEVICE.

Application filed July 6, 1921. Serial No. 482,701.

To all whom it may concern:

Be it known that I, FREDERICK W. DUSCHE, a citizen of the United States, and a resident of East Orange, in the county of Essex and State of New Jersey, have invented new and useful Improvements in Shoe-Shining Devices, of which the following is a specification.

This invention relates to shoe-polishing devices, one object of the invention being to provide a device of this character embodying novel features of construction whereby both the toe portion and heel portion of a shoe can be polished with ease by manipulation of the cloth by one hand of the operator while in a sitting position.

Further objects of the invention are to provide a device of the character described including a spring-actuated roller for the polishing cloth which automatically winds the cloth thereon, and a guide for said roller over which the same can be moved to various positions relative to the shoe, whereby the cloth can be used for polishing both the toe portion and heel portion of a shoe and manipulated by one hand of the operator; to provide novel and effective guide means for the roller and the polishing cloth whereby a shoe can be polished with the utmost ease; to provide a shoe-polishing device including a stand or block to support the shoe, a spring-actuated roller mounted on the stand to wind the cloth so that the operator need pull the cloth in one direction over the shoe with one hand and the spring of the roller pulls the cloth in the opposite direction in winding the cloth on the roller; to provide a novel mounting for the roller to adapt it to be used in polishing both the toe portion and the heel portion of a shoe without moving the shoe; to provide a shoe-polishing device which is simple and inexpensive in construction, and to obtain other results and advantages as may be brought out by the following description.

Referring to the accompanying drawings, in which like numerals of reference indicate the same parts throughout the several views,

Figure 1 is a perspective view of a shoe-polishing device constructed in accordance with my invention, showing the polishing roller arranged at one side of the block in position for polishing the toe portion of a shoe;

Figure 2 is an end view of the device as

shown in Figure 1, showing the polishing cloth in position for polishing the toe portion of a shoe;

Figure 3 is a side elevation of the device showing the roller and polishing cloth in position for polishing the side and heel of a shoe;

Figure 4 is a top plan view of the device as illustrated in Figure 3, and

Figure 5 is a longitudinal sectional view through the roller showing the details of construction.

In the embodiment of my invention shown in the drawings the reference character 1 designates a block or stand which is of a size to conveniently support a shoe. The block is preferably rectangular, and a guide 2 is secured to the block and extends along one side and one end thereof to support a polishing-cloth roller 3. In the present instance the guide 2 comprises a length of heavy wire which has one end thereof secured to the side of the block by means of staples or like fastening members 4, the wire being disposed in spaced and substantially parallel relation with the said side of the block to the end thereof. The wire is then bent upwardly at substantially right angles as at 5, and then parallel to the end of the block as at 6, the other extremity of 75 the wire being then bent downwardly as at 7 and secured to the end of the block by means of fastening members 8. At the side of the block opposite the guide 2 is provided another guide 9 which is preferably formed of heavy wire similar to the guide 2 and has its ends returned and secured in the block as indicated at 10.

The roller 3 is revolvably mounted on a shaft 11 the ends of which are secured in the arms of a U-shaped yoke 12, and springs 13 are connected between the roller and the said yoke 12 for the purpose of influencing revolution of the roller in one direction.

In the present instance the springs are shown as housed within recesses 14 in the ends of the roller 11 and bushings 15 are interposed between the inner ends of said recesses and the arms of the yoke to space the ends of the roller from said arms. Substantially centrally of its length the yoke 12 is provided with an eye 16 which has a swivel connection as at 17 with the yoke, the eye 16 being adapted to slide on the guide 2 as shown in Figures 1 and 2. A

polishing cloth 18 has one end thereof secured in any suitable manner to the roller 3, the said polishing cloth being normally wrapped or wound around the said roller.

5 When it is desired to polish the toe portion of a shoe the shoe is placed upon the block 1 as shown in Figure 4. The free end of the polishing cloth 18 is then pulled from the roller 3 against the action of the springs 13 and slipped downwardly beneath the guide 9 as shown in Figure 2. The operator then grasps the free end of the polishing cloth and pulls the same from the roller 3 over the top of the shoe a sufficient distance and then relieves the tension on the cloth, whereupon the springs 13 wind the cloth upon the roller drawing the same over the top of the shoe in the opposite direction. In this manner the constant reciprocation of the polishing cloth in opposite directions polishes the shoe. This operation can be conveniently executed with the operator in a sitting position, the weight of the foot holding the block 1 on the floor 10 or other support and only one hand being necessary to reciprocate the polishing cloth.

When it is desired to polish the side and heel of the shoe, the yoke 12 is moved along the guide 2 upwardly along the portion 5 of the guide onto the portion 6 thereof into a substantially vertical position as shown in Figures 3 and 4. The swivel connection of the eye 16 to the yoke permits this movement of the yoke into vertical position and for the purpose of maintaining the yoke in the desired position the portion 6 of the guide may be formed with crimps 19 to receive the eye 16. With the roller 3 in this position the polishing cloth is pulled from the roller along the side of the shoe and around the heel as shown in Figure 4, the strip being reciprocated by the one hand of the operator and the springs of the roller as above described. To polish the opposite side of the shoe the yoke 12 is slid along the portion 6 of the guide to the other end thereof and the eye 16 dropped into the crimp 19, the polishing cloth being unwound from the roller and around the side and heel 45 of the shoe in the direction opposite to that shown in Figure 4 of the drawing.

With this construction it will be noted that both the toe portion and heel portion of a shoe can be polished with the utmost ease and with the operator in a sitting position. The swivel connection of the eye 16 with the yoke 12 enables the roller 3 and the polishing cloth to accommodate themselves to the top of the shoe and allow a 55 certain flexibility of movement which is desirable in effectively polishing the shoe.

Obviously, many modifications and changes can be made in the detail construction of the guides and the roller, as well as 60 the block 1, without departing from the

spirit or scope of the invention, and therefore I do not desire to be understood as limiting myself except as required by the following claims when construed in the light of the prior art. 70

Having thus described the invention, what I claim is:

1. A shoe polishing device including a stand, a guide on said stand, a yoke slidably and hingedly connected to said guide, a spring roller in said yoke, and a polishing strip attached at one end to said roller and wound thereon. 75

2. A shoe polishing device including a stand, a spring roller, a polishing strip attached at one end to said roller and wound thereon, and a guide for said roller mounted on said stand so that the roller may be moved from one side of the stand to another. 80

3. A shoe polishing device including a stand, a spring roller, a polishing strip attached at one end to said roller and wound thereon, a guide for said roller mounted on said stand, and means slidable on said guide for mounting said roller so that it may be 85 bodily moved relative to said stand.

4. A shoe polishing device including a stand, a spring roller, a polishing strip attached at one end to said roller and wound thereon, and a guide for said roller mounted on said stand and comprising continuous angularly disposed portions along which said roller is adapted to move. 95

5. A shoe polishing device including a stand, a rod forming a guide, a yoke having an eye slidably receiving said rod, a spring roller in said yoke, and a polishing strip attached at one end to said roller and wound thereon. 100

6. A shoe polishing device including a stand, a spring roller, a polishing strip attached at one end to said roller and wound thereon, a continuous guide for said roller mounted on said stand including a portion arranged in spaced parallel relation with one side of said stand and substantially in the plane of the top thereof and another portion arranged at an angle to said first-mentioned portion and in spaced relation to the top of said stand, and means for movably mounting said roller on said guide so as to be disposed substantially parallel with the top of said stand when on said first-mentioned portion of the guide and at substantially right angles to said top of the stand when on said second-mentioned portion of the guide. 110

7. A shoe polishing device including a stand, a spring roller, a polishing strip attached at one end to said roller and wound thereon, a guide for said roller mounted on said stand, a support in which said roller is journaled, and means movable on said guide and having a swivel connection with said 125 roller support. 130

8. A shoe polishing device including a stand, a spring roller, a polishing strip attached at one end to said roller and wound thereon, a guide for said roller mounted on 5 said stand, a U-shaped yoke adapted to receive said roller between its arms, and means movable on said guide and having a swivel connection with the base of said yoke.
9. A shoe polishing device including a 10 stand, a spring roller, a polishing strip attached at one end to said roller and wound thereon, a guide having portions at the sides and one end of said stand, and means for mounting said roller on said guide so

that the roller is free to turn on an axis 15 perpendicular to that portion of the guide supporting it.

10. A shoe polishing device including a stand, a spring roller, a polishing strip attached at one end to said roller and wound 20 thereon, a guide having portions at the sides and one end of said stand, means for mounting said roller on said guide, and means for positioning the roller at a predetermined point of the length of the end portion of 25 said guide.

FREDERICK W. DUSCHE.
